UNITED STATES PATENT OFFICE.

JOHN F. FISHER, OF BROOKPORT, ILLINOIS, ASSIGNOR OF ONE-HALF TO
ELISHA BAUGH, OF BROOKPORT, ILLINOIS.

RUDDER-BLADE FOR STEAM VESSELS.

SPECIFICATION forming part of Letters Patent No. 772,794, dated October 18, 1904.

Application filed December 8, 1903. Serial No. 184,309. (No model.)

To all whom it may concern:

Be it known that I, JOHN F. FISHER, a citizen of the United States, residing at Brookport, in the county of Massac and State of Illinois, have invented new and useful Improvements in Rudder-Blades for Steam Vessels, of which the following is a specification.

This invention relates to an improved rudder-blade for steam vessels and any other craft 10 propelled by power other than steam; and the primary object of the same is to provide a simple and effective form of rudder having a propeller located therein which will not carry a swell of dead water after the stern of the 15 boat, as in the ordinary form of rudder, and also enable a boat equipped with the same to be more quickly turned in a shorter arc than is now possible and to dispose the bow or stern of the vessel in a positive position, as 20 may be required in approaching a landing or at any other point, irrespective of the resistance offered by wind or current. The improved rudder mechanism is so constructed that the shaft controlling the operation of the 25 same may be disconnected from the motor power in case of accident to adapt the propeller to be manually operated direct.

Another advantage of the improved rudder construction is that a boat embodying the 30 same may be turned under full speed without listing or careening, and when used on a naval vessel the bow of the latter can be held toward the enemy to perform certain tactics, and turn can be made within the length of 35 the vessel, and any position desired may be obtained by the helmsman, who has absolute control of the improved apparatus.

The invention consists in the construction and arrangement of the several parts, which 40 will be more fully hereinafter set forth.

The drawing illustrates a longitudinal section of the rear portion of a vessel, showing the improved rudder applied thereto, the latter having a part thereof broken away.

45 The numeral 1 designates the stern-post of a vessel, and 2 the keelson. The stern-post at a suitable point above the keelson is formed with a vertical slot 3, and extending through

said post is the rear end of a driving-shaft 4, having a crank 5 at its inner end adapted to 50 be suitably connected to an engine or other motor. The shaft 4 is preferably made in two sections and connected by a coupling 6, so that in the event of accident to the motor the improved rudder structure will not be impaired and the part of the shaft connected to the engine may be detached from the rear section of said shaft, and steering means may then be used without the propelling means 55 hereinafter set forth.

The rudder comprises a blade 7 of usual contour and dimensions and a post 8, having an offset 9 in an outward direction at an intermediate point. At the upper and lower terminals of the offset or at the point where 65 the said offset continues into the upper and lower vertical portions of the post 8 metallic bearings 10 are secured to receive the upper and lower ends of a power-transmitting shaft 11, which is also engaged at an intermediate 70 point by a bearing-strap 12, secured to the stern-post 1 and adjacent rear portion of the vessel. A rabbet 13 is formed in the lower inner part of the rudder to permit the rudder to swing freely over a rear extension of the 75 keelson, and rising from said extension is a fulcrum stud or pin 14, which is fitted in the lower vertical portion of the rudder-post 8. Adjacent to the offset 9 of the rudder the blade 7 of the latter has a propeller-opening 15 formed 80 therein, and extending across the center of said opening in the longitudinal direction of the rudder is a propeller-shaft 16, on which is secured a propeller 17 of any suitable form. The propeller-shaft projects inwardly beyond 85 the inner edge of the offset 9 of the rudder-post and has a miter-gear 18 keyed thereon, which is held in continual mesh with a corresponding miter-gear 19, keyed on the shaft 11. Above the bearing-strap 12 another miter- 90 gear 20 is keyed on the shaft 11 and in a position reverse to the gear 19, the said gear 20 meshing with a miter-gear 21 on the rear projecting end of the shaft 4. The recesses 3 in the stern-post 1 and the offset 9 of the rudder- 95 post 8 form an open space in which to dispose

the miter-gears just described, so that the rudder as an entirety may be fitted closely against the rear of the vessel.

In the operation of the mechanism as set forth motion is imparted to the shaft 4, which operates the gears 21, 20, and 19 and the shaft 16 through the medium of the gear 18, thereby rotating the propeller 17, the direction of movement of the propeller depending upon the direction of rotation of the shaft. The rudder will be turned at different angles by the usual steering means, and the propeller is equally shifted therewith without in the least disturbing the engaging relation of the gears, and by having the propeller located in the rudder the disadvantageous effect of dead-water swells at the stern of the boat will be avoided and steering of the latter will be rendered materially sensitive. Other advantages heretofore noted will also result from the use of the improved rudder carrying the propeller as set forth, and to accommodate different applications it will be understood that changes in the proportions, dimensions, and minor details may be resorted to without in the least departing from the spirit of the invention.

Having thus fully described the invention, what is claimed as new is—

The combination with the stern of a vessel, of a stern-post having a rearwardly-opening vertically-extending recess therein, a sectional shaft extending through the stern-post into the upper part of said recess and having

a miter-gear on its rear end within the recess, a rudder having a blade with a post at the inner terminal thereof and an opening therethrough adjacent to said post, the post being offset adjacent to its point of attachment to the blade to provide a seat having metallic bearings at the upper and lower terminals thereof, a power-transmitting shaft vertically disposed in the said seat and having its ends extending into the bearings, reversely-positioned miter-gears keyed on the said vertical power-transmitting shaft and spaced apart from each other, the upper gear being held in continual mesh with the similar gear on the rear end of the sectional shaft, a bearing-strap on the vertical shaft between the miter-gears and connected to the stern-post, the recess in the stern-post and the seat on the rudder-post permitting the said rudder-post to be closely arranged in relation to the stern-post and permit the gears to have ample room for operation, and a propeller-shaft extending across the opening in the rudder-blade and having a propeller thereon movable through said opening, and a miter-gear on its inner terminal meshing with the lower similar gear of the power-transmitting shaft.

In testimony whereof I affix my signature in presence of two witnesses.

JOHN F. FISHER.
